HAIRDRESSING TOOL

Herman C. Schlicker, Brooklyn, N. Y., assignor to
 Rollocurl Corporation, New York, N. Y., a corporation of New York

Application February 10, 1940, Serial No. 318,235

11 Claims. (Cl. 132—35)

This invention relates to hair curling devices, and more particularly relates to novel hair curlers having means for selectively controlling bob pins used with the device.

The hair curling device of the present invention comprises a mandrel having a longitudinal slot for laterally receiving a comb insert, which when extended is used for forming a curl of hair and when inserted within the mandrel permits removal of the curl onto an attached bob pin. In accordance with the present invention, the bob pin is partially inserted into an end of the mandrel and remains inactive during the hair curling operation. When the curl is completely formed, means are provided in the device of the invention to permit the bob pin to be fully inserted into the mandrel and spread apart to receive the hair curl upon its removal from the mandrel. The hair curling tool proper is preferably of the type disclosed and in the co-pending application, Serial No. 306,040, assigned to the same assignee as is the present case.

It is accordingly an object of the present invention to provide a novel hair curling device which receives a bob pin at one end thereof for selectively different depths of insertion.

A further object of the present invention is to provide a novel hair curling device having a slotted mandrel which receives a comb insert, and one end of which receives a bob pin for selectively different depths of insertion.

Still a further object of the present invention is to provide a novel hair curling device having a mandrel with a coacting retractable comb insert and means for controlling the degree of insertion of a bob pin in an end of the mandrel in accordance with the position of the retractable comb insert in the mandrel.

These and further objects, advantages, and features of the present invention will appear in the subjoined detailed description of specific embodiments thereof, illustrated in the accompanying drawings in which—

Figure 1 is a plan view of one embodiment of the hair curling device.

Figure 2 is an elevational view thereof, with the comb insert in the extended position.

Figure 3 is an elevational view of the hair curling device corresponding to Figure 2, with the mandrel portion thereof in cross-section.

Figure 4 is a transverse cross-sectional view through the hair curler of Figure 1, taken along the line 4—4 thereof.

Figure 5 is an enlarged cross-sectional view of a portion of the hair curler of Figure 1 showing

the position of the coacting bob pin when the comb insert is in the extended position.

Figure 6 is an enlarged cross-sectional view of a portion of the hair curler of Figure 1 with the comb insert in the retracted position, showing the corresponding position of the coacting bob pin.

Figure 7 is a cross-sectional view through a hair curling device provided with the means for projecting, retracting and maintaining the comb of the same as disclosed in Figures 1 to 3 having a modified arrangement for selectively controlling the position of the coacting bob pin.

Figure 8 is a cross-sectional view through the modified form of the curler, corresponding to Figure 7, with the bob pin fully inserted therein.

Figure 9 is a cross-sectional view through a further modified form of the hair curling device provided with the means for projecting, retracting and maintaining the comb of the same as disclosed in Figures 1 to 3, with the bob pin and comb insert in the extended positions.

Figure 10 is a cross-sectional view through the hair curling device corresponding to Figure 9, with the bob pin in the fully inserted position and the comb insert correspondingly retracted.

The hair curling device per se may assume optional forms in practice. The general arrangement of the hair curler preferably corresponds to the form disclosed in the application Serial No. 306,040, previously referred to. However, other curler forms may be employed in conjunction with the bob pin selective positioning means to be described.

35 The hair curler shown in Figures 1 and 2, respectively plan and elevational views, comprises a transversely slotted mandrel 10 having a comb insert 11 laterally coacting therewith. A thumb member 12, 13 extending from the mandrel is secured with comb 11 for manually changing its position from the extended and retracted positions. A regular hair comb section 14 extends from one end of mandrel 10, the same being a handle for the hair curling section of the device.

40 45 The free end of mandrel 10 incorporates an "acorn" shaped end portion 15 which in cross-section defines a "ridge and valley" formation, and is provided with a central longitudinal opening 16 for receiving the bob pin.

50 55 The cross-sectional view through the hair curler, Figure 3, illustrates a preferred manner for operating comb insert 11 with respect to longitudinally slotted mandrel 10. A leaf spring 17 is positioned between the inside edge 17 of retractable comb 11 and the inside surface 18 of

mandrel 10. Leaf spring s is arranged to mechanically bias comb insert 11 normally outwardly of mandrel 10 to the extended position shown in Figures 2 and 3. A cam plate 20 is arranged within thumb operated member 12, 13, spring pressed by contained compression spring 22 against transverse pin 21 set in the shank of mandrel 10. Cam plate 20 permits lateral displacement of comb insert 11 and maintains the comb insert stably in extended or retracted position.

Figure 4, a transverse cross-sectional view near the tip of the mandrel 10, shows comb insert 11 in the extended position as well as the relatively displaced positions of central opening 16 of mandrel 10, transverse opening 32 of comb insert 11, and opening 24 of portion 25 of leaf spring s.

In accordance with the present invention means are provided to limit the degree of insertion of a bob pin p mounted under tension at the mandrel end 15 until the curl of hair is wound prior to removal from the mandrel.

Enlarged cross-sectional view Figure 5 illustrates one embodiment for carrying out the invention. End portion 25 of leaf spring s is arranged to abut tip 26 of shank 27 of bob pin p when it is inserted and maintained during curl winding in central opening 16 of mandrel 10. Comb insert 11 is then in the extended position, as shown, and is used for spacedly gripping the hair to curl it about mandrel 10 in the usual manner. The humped or sinuous shank 28 of bob pin p grips the complementary "acorn" end 15 of mandrel 10 under tension. The bob pin is accordingly gripped onto mandrel 10 of the hair curler and held stably under tension in readiness for further coaction with the curled hair. The bob pin is in this manner maintained out of the way, preventing interference with the hair curling operation.

After the hair curl is formed about mandrel 10, indicated at 30 in Figure 6, it is ready for removal from the mandrel and gripping by bob pin p. Thumb member 12, 13 is pressed to move comb insert 11 to the retracted or disappearing position within the transverse slot of mandrel 10, as indicated in Figure 6. When comb insert 11 is thus retracted against the pressure of leaf spring s, it remains there due to the action of spring pressed cam plate 20 against pin 21, as shown in Figure 3. The bottom surface 17 of comb insert 11 straightens out leaf spring s, as illustrated, and moves the vertical end portion 25 of the spring further within mandrel 10.

When comb insert 11 is in the fully retracted position shown in Figure 6, hole 24 of upright spring portion 25 becomes aligned with opening 16 of mandrel 10. A longitudinal series of openings 32 of predetermined extent is arranged in the bottom portions of a corresponding number of teeth of comb insert 11, as illustrated. The tip 26 of straight shank 27 of bob pin p when fully inserted will accordingly abut the first tooth t of comb insert 11 having no opening 32. When the bob pin is fully inserted, its arms are spread and extended as shown, with the humped shank 28 thereof extending angularly and over a portion of hair curl 39 preparatory to receiving the curl. The curl of hair 39 is then moved between the shanks of the bob pin, and removed from mandrel 10 to be gripped by both shanks of the bob pin as tension thereon is released to maintain it in the curled form.

Figures 7 and 8 illustrate a further form for carrying out the bob pin control feature of the 75

invention for the hair curling device. In Figure 7 the comb insert 11 is in extended position with respect to the mandrel, and the bob pin p is partially inserted in the mandrel with the humped shank 28 thereof gripped onto the "acorn" 15 of the mandrel. A projection 35 extends beneath the edge of comb insert 11 and abuts the tip 26 of inserted bob pin p as shown in Figure 7. The projection 35 of the comb insert 11 serves to limit the insertion of bob pin p in the manner of spring portion 25 of the previous form. The projection 35 is received in pocket 36 formed in the mandrel 10'. Although the comb insert 11, as illustrated in this embodiment, is operable for reaction by the thumb operated member 12, 13, there may be applied in this embodiment, if desired, a leaf spring to mechanically bias the comb insert normally outward of the mandrel 10.

The form of the invention of Figures 7 and 8 requires a mandrel with a relatively deeper diameter for a given size of comb insert than does the previously described form, in view of projecting portion 35. The opening 16 in mandrel 10' is accordingly eccentrically placed with respect to the longitudinal axis of the mandrel to properly coact with the series of openings 32 in comb insert 11, as shown. With the comb in the retracted position of Figure 8 openings 32 of comb insert 11 are opposite opening 16 of mandrel 10' and the straight shank 27 of the bob pin is permitted to be fully inserted until the tip 26 of the bob pin abuts tooth t of comb 11 with no opening 32. The bob pin is then ready to receive the curl of hair which is removed from the mandrel when completed, in the manner previously described.

Figures 9 and 10 illustrate a further form for carrying out the present invention. In this form a spring operated control member 40 for the bob pin is attached to the end 41 of comb insert 11, adjacent the opening 16 of mandrel 10. Member 40 limits the insertion depth of bob pin p by abutting the tip 26 thereof when comb 11 is in the extended position shown. Compression spring 42, extending from a recess 43 in end 41 of comb 11, presses member 40 to the downward or abutting position. When comb insert 11 is in the retracted or disappearing position shown in Figure 10, abutting member 40 is displaced with respect to tip 41 of comb 11 due to action of compression spring 42. When the comb is thus retracted, opening 45 in member 40, as well as series of openings 32 of comb 11, are in alignment with central opening 16 of mandrel 10. The shank 27 of bob pin p may then be fully inserted until its tip 26 abuts tooth t of comb 11. The bob pin is then prepared to receive the curl in the manner previously set forth. The spring controlled abutting member 40 performs the selective bob pin control action without requiring an increased mandrel diameter.

It is obvious that various changes and modifications may be made to the details of construction and arrangement illustrated without departing from the general spirit and scope of the invention as set forth in the following claims.

I claim:

1. A hair curling device comprising a longitudinally slotted member, a comb insert arranged for lateral displacement into and out of the slot of said member and having an opening of predetermined length arranged opposite an opening through an end of said member when said comb insert is in the retracted position with said member to permit an arm of a bob pin to be inserted through said member and insert openings, and

means on said comb insert for limiting the insertion of a bob pin arm in said member opening when said comb insert is in the extended position.

2. A hair curling device comprising a longitudinally slotted mandrel, a comb insert arranged for lateral displacement into and out of the slot of said mandrel and having a longitudinal opening of predetermined length, said opening being arranged opposite a longitudinal opening through an end of said mandrel when said comb insert is in the retracted position within said mandrel to permit an arm of a bob pin to be inserted through said mandrel and insert openings, and means on said comb insert for limiting the insertion of a bob pin arm to a predetermined intermediate length into said mandrel opening when said comb insert is in the extended position.

3. A hair curling device comprising a longitudinally slotted member, a comb insert arranged for lateral displacement into and out of the slot of said member and having a series of openings of a predetermined length with an abutment at the end of said openings, said openings being arranged opposite an opening through an end of said member when said comb insert is in the retracted position within said member to permit an arm of a bob pin to be inserted through said member opening and insert openings, and means on said comb insert for limiting the insertion of a bob pin arm up to said comb insert when said comb insert is in the extended position.

4. A hair curling device comprising a longitudinally slotted mandrel, a comb insert arranged for lateral displacement into and out of the slot of said mandrel and having a longitudinal series of openings through the teeth of the comb for a predetermined length, said openings being arranged opposite a longitudinal opening through an end of said mandrel when said comb insert is retracted within said mandrel to permit an arm of a bob pin to be inserted through said mandrel opening and insert openings, and means on said comb insert for limiting the degree of insertion of a bob pin arm into said device through said mandrel opening when said comb insert is in extended position.

5. A hair curling device comprising a longitudinally slotted member, a comb insert arranged for lateral displacement into and out of the slot of said member and having an opening of predetermined length arranged opposite an opening through an end of said member when said comb insert is in the retracted position with said member to permit an arm of a bob pin to be inserted through said member and insert openings, and means on said comb insert for limiting the insertion of a bob pin arm in said member opening when said comb insert is in the extended position, comprising a projection extending from said comb insert adjacent the member opening.

6. A hair curling device comprising a longitudinally slotted member, a comb insert arranged for lateral displacement into and out of the slot of said member and having an opening of predetermined length arranged opposite an opening through an end of said member when said comb insert is in the retracted position with said member to permit an arm of a bob pin to be inserted through said member and insert openings, and means on said comb insert for limiting the insertion of a bob pin arm in said member opening when said comb insert is in the extended position, comprising an abutting element depending from said comb insert and spring biased to block said

pin arm at said member opening when said comb insert is extended.

7. A hair curling device comprising a longitudinally slotted member, a comb insert arranged for lateral displacement into and out of the slot of said member and having an opening of predetermined length arranged opposite an opening through an end of said member when said comb insert is in the retracted position with said member to permit an arm of a bob pin to be inserted through said member and insert openings, and means on said comb insert for limiting the insertion of a bob pin arm in said member opening when said comb insert is in the extended position, comprising an abutting element depending from said comb insert and spring biased to block said pin arm at said member opening when said comb insert is extended and arranged to be moved against the spring bias action when said comb insert is retracted to present an opening thereof in alignment with said openings to selectively permit said pin arm to be fully inserted into said insert openings.

8. A hair curling device comprising a longitudinally slotted mandrel, a comb insert arranged for lateral displacement into and out of the slot of said mandrel and having a longitudinal opening of a predetermined length, said opening being arranged opposite a longitudinal opening through an end of said mandrel when said comb insert is in the retracted position within said mandrel to permit an arm of a bob pin to be inserted through said mandrel and insert openings, and means on said comb insert for limiting the insertion of a bob pin arm to a predetermined intermediate length into said mandrel opening when said comb insert is in the extended position, comprising an abutting element depending from said comb insert adjacent said mandrel opening and spring biased to block said pin arm at said mandrel opening when said comb insert is extended, and arranged to be moved by said insert against the spring bias action when said comb insert is displaced to the retracted position.

9. A hair curling device comprising a longitudinally slotted mandrel, a comb insert arranged for lateral displacement into and out of the slot of said mandrel and having a longitudinal series of openings through the teeth of the comb for a predetermined length, said openings being arranged opposite a longitudinal opening through an end of said mandrel when said comb insert is retracted within said mandrel to permit an arm of a bob pin to be inserted through said mandrel opening and insert openings, and means on said comb insert for limiting the degree of insertion of a bob pin arm into said device through said mandrel opening when said comb insert is in the extended position, comprising an abutting element adjacent said mandrel opening and arranged to be moved by said insert when said comb insert is displaced to the retracted position.

10. A hair curling device comprising a longitudinally slotted mandrel, a comb insert arranged for lateral displacement into and out of the slot of said mandrel and having a longitudinal series of openings through the teeth of the comb for a predetermined length, said openings being arranged opposite a longitudinal opening through an end of said mandrel when said comb insert is retracted within said mandrel opening and insert openings, and means on said comb insert for limiting the degree of insertion of a bob pin arm into said device through said mandrel opening when said comb insert is in the extended position,

comprising an abutting element adjacent said mandrel opening and arranged to be moved by said insert when said comb insert is displaced to the retracted position, to present an opening thereof in alignment with said openings to selectively permit said pin arm to be fully inserted into said insert openings.

11. A hair curling device comprising a longitudinally slotted member, a comb insert arranged for lateral displacement into and out of the slot of said member and having a series of openings of a predetermined length with an abutment at the end of said openings, said openings being arranged opposite an opening through an end of said member when said comb insert is in the retracted position within said member to permit an

arm of a bob pin to be inserted through said member opening and insert openings, and means on said comb insert for limiting the insertion of a bob pin arm up to said comb insert when said comb insert is in the extended position, comprising an abutting element depending from said comb insert adjacent said member opening and spring biased to block said pin arm at said member opening when said comb insert is extended, and arranged to be moved by said insert against the spring bias action when said comb insert is retracted to present an opening thereof in alignment with said openings to selectively permit said pin arm to be fully inserted into said insert openings.

HERMAN C. SCHLICKER.
